STAPLING MACHINE

Harold S. Heller, Cleveland Heights, Ohio

Application December 8, 1941, Serial No. 422,077

5 Claims. (Cl. 1—49)

This invention relates to improvements in staple driving machines, and more particularly to means for cutting and driving a fastener of particular shape by use of a single machine.

An object of the present invention is to provide and drive a fastener having the characteristics of a brad. In the form of the invention here disclosed, a pair of these fasteners are cut from a standard U-shape staple and driven simultaneously. The invention resides in the various parts adapted for carrying out the invention, as will more clearly appear from the accompanying drawing and description, and the essential features of the invention will be set forth in the claims.

In the drawing, Fig. 1 is a side elevational view of a stapling machine embodying my invention; Fig. 2 is an enlarged fragmental view of the lower right-hand portion of Fig. 1, the gate being in a lowered position; Fig. 3 is a fragmental front elevational view of the lower right-hand portion of Fig. 1, taken in approximately the position indicated at 3—3, Fig. 1; Fig. 4 is a view similar to Fig. 3 with certain parts broken away and in section so as to more clearly show the construction; Fig. 4a is a view similar to Fig. 4 and showing two brad-like fastening elements as cut from a standard staple and simultaneously driven into a piece of molding for the securement thereof to a screen frame; Fig. 5 is a bottom view of the structure shown in Fig. 3; Fig. 6 is a plan view illustrating the screen frame and molding of Fig. 4a, the screen molding being secured by the use of the present fastening elements; and Fig. 7 is a vertical sectional view on the line 7—7 of Fig. 6.

The staple machine here illustrated for the disclosure of the present invention is similar in many respects to the machine shown in United States Patent No. 1,996,640, granted April 2, 1935 to Francis M. Case. Therefore only a brief description will be given of the parts similar in the two machines.

The upper part of the machine comprises a hollow casing 10 formed of a main frame and a cover frame and providing a hand grip at 11 and a vertically extending square housing at 12 in which reciprocates a plunger 13 having a rubber cap 14 adapted to be struck in effecting downward movement of the plunger. A spring, not shown, normally biases the plunger 13 to its uppermost position. The base of the machine comprises a staple guide bar 15 of generally inverted T-form shape upon which slide the U-shape staples 16 which are usually connected as a group

by suitable adhesive which permits the staples, one by one, to be readily sheared from the group. A U-shape follower 17 rides on the bar 15 behind the staples so as to feed them to the driving position beneath a driving blade carried by the plunger 13. This follower is pulled forwardly by a spring enclosed in the housing 10 and having one of its ends attached to the follower at 18. When loading the machine with staples, the follower is latched in its rearmost position and a flat spring 19 is provided to hold the follower in latched position. At the forward end of the guide bar an inverted U-shape front guide 20 is secured to the bar by pins or rivets 21. The inner face of this guide 20, as best seen in Fig. 4, is spaced from the end of bar 15, as indicated at 22, for the passage of the staples to a position beneath the plunger driving blade. A front gate 23 is pivotally mounted on a pin 24 in a slot 20a in the guide 20, this slot permitting the gate to be dropped to the position shown in Fig. 2 for the purpose of sliding a group of staples onto the bar 15 from the front end thereof. After such a loading of the machine with staples, the gate 23 is swung upwardly to the position shown in the other views, where it rests on two side lips 20b of the guide 20 and is held by the gate latch 25 which is reciprocably mounted in the bent-over guide portions 10a of the housing 10. A tongue 23a struck up from the front wall of the gate 23 provides a stop which limits the downward movement of the gate latch 25. Thus the gate prevents the staples 16 from being moved forwardly out of the machine under the action of the spring-pressed follower 17. All of the above described parts are like those shown in the above mentioned Case patent, to which further reference may be had if desired.

In carrying out the present invention, in the stapling machine here illustrated, an anvil 26, here shown as of inverted T-shape cross section, is rigidly mounted, by means of the pins 21, in a slot in the forward end of the staple supporting bar 15, and projecting forwardly from such bar 45 is an anvil lip 26a of generally rectangular cross section.

Suitably secured to the plunger 13 for movement therewith, and lying along the front face thereof, is a driving blade 27. As shown in Figs. 4 and 4a, the lower end of this plunger blade is centrally notched or recessed, as at 28, for cooperation with the anvil lip 26a in shearing from each staple, during the driving thereof, the middle portion 16a of the staple crown, and in simultaneously driving into the work the spaced staple

legs and the short crown end portions at the tops thereof. To that end, the side edge portions 27a of the lower end of the plunger blade are so spaced by the plunger blade notch or recess 28 as to more or less snugly receive therebetween, as the plunger blade is depressed, the anvil lip 26a. Thus, during the driving of each staple, downward movement of the middle portion 16a of the staple crown is arrested by the anvil lip 26a, with the consequent removal of such staple crown portion, by shearing, as downward movement of the plunger blade 27 continues. Before such shearing of the middle portion of the staple crown occurs, the staple legs 16 are started into the work, and as the downward movement of the plunger blade continues, the two staple legs, each with a short end portion 16" of the staple crown at the top thereof, are completely driven into the work by the correspondingly spaced side edge portions 27a of the plunger blade 27. During such shearing and driving operation, the plunger blade recess 28 receives the anvil lip 26a and the severed middle portion 16a of the staple crown, as will be evident from Fig. 4a.

Therefore, during each driving operation, two separate brad-like fastening elements are simultaneously formed from each staple and simultaneously driven into the work, the headed portions 16" of said fastening elements being imbedded in the work, flush with the top surface thereof, if desired. For purposes of illustration, these brad-like fastening elements are here shown (see Figs. 4a, 6 and 7) for the securing of a molding strip 28a to a screen frame 30, with the screen 29 interposed therebetween. Pairs of these fastening elements may be easily and rapidly driven into the work, with the fastening being effected in a neat and attractive manner.

For the outward passage from the stapling machine of the severed middle portions 16a of the staple crowns, a suitable opening 23b is provided in the front wall of the pivoted gate 23, as best shown in Fig. 3. This opening is of somewhat greater width than the anvil lip 26a and hence of somewhat greater width than the severed staple crown portions, the width of the anvil lip determining, of course, the length of the staple crown portions which are severed by shearing. Usually, the severed staple crown portions automatically leave the stapling machine through the gate opening 23b, so that no attention thereto need be given in use of the present stapling machine.

To those skilled in the art to which the present invention relates, other features and advantages

thereof will be evident from the foregoing description of one embodiment of such invention.

What I claim is:

1. In a stapling machine, means for holding a staple, said staple having a top portion and two depending leg portions, means for driving said leg portions, and means underlying and engaging at least a part of said top portion and coacting with said driving means for shearing away at least a part of said top portion by operation of said driving means.

2. In a staple driving machine, a vertically reciprocable plunger blade, means for feeding a staple beneath said plunger blade, said staple having a top portion and two depending leg portions, said plunger blade having two spaced portions adapted to overlie and drive said staple leg portions, and a fixed anvil adapted to underlie and engage that part of said staple top portion which is disposed between said spaced plunger blade portions, whereby to shear off such part of said top portion and to drive said separated leg portions by movement of said plunger blade.

3. In a stapling machine, means for holding a staple having spaced leg portions and a connecting portion therefor, a pair of cooperable means for severing said staple connecting portion, and means for producing relative movement between said cooperable means to sever such staple connecting portion and for continuing such movement to effect the simultaneous driving of the separated staple leg portions into staple-receiving material.

35 4. In a stapling machine, means for holding a staple having spaced leg portions and a connecting portion therefor, a pair of cooperable means for severing said staple connecting portion, means for producing relative movement between said cooperable means to sever such staple connecting portion and for continuing such movement to effect the simultaneous driving of the separated staple leg portions into staple-receiving material, and means having an opening for the discharge from the stapling machine of the severed staple connecting portion.

5. In a stapling machine, means for holding a staple, said staple having two spaced leg portions and a crown portion therebetween, means for driving said leg portions, and means underlying and engaging the middle part of said crown portion and coacting with said driving means for shearing away said middle part of said staple crown portion, by operation of said driving means.

HAROLD S. HELLER.
